UNITED STATES PATENT OFFICE

2,564,909

RAILWAY CAR

Otto A. Kuhler, Blauvelt, N. Y., and William E. Burnett, Montclair, N. J., assignors to American Car and Foundry Company, New York, N. Y., a corporation of New Jersey

Application April 11, 1947, Serial No. 740,743

13 Claims. (Cl. 105—340)

1 This invention relates to railway cars and more particularly to railway sleeping cars.

The trend in sleeping car design is to provide fully enclosed rooms or compartments for the passengers instead of curtained upper and lower berths. A single deck sleeping car divided into fully enclosed compartments will accommodate fewer passengers than cars with curtained upper and lower berths, so it has been necessary to establish a higher passenger fare rate in order to maintain the pay load value of such a car. An object of the present invention is to provide a plural deck sleeping car for accommodating a maximum number of passengers in private compartments whereby the individual passenger fare rate can be reduced to a minimum.

Another object of the invention is to provide a sleeping car within allowable dimensions that will accommodate a maximum number of passengers.

Another object of the invention is to provide a plural deck sleeping car wherein a maximum number of passengers may be accommodated and with adequate storage space for equipment and accessories.

A further object of the invention is to provide a sleeping car with one deck having rooms on each side of a center aisle substantially the full length thereof and with a lower deck having a center aisle with rooms on both sides thereof substantially the car length between the wheel trucks.

Another object of the invention is to provide a double deck sleeping car with the lower deck having dead ends and connected by interior steps with the upper deck at one side and midway of the car.

These and other objects of the invention will be apparent to those skilled in the art from a study of the following description and accompanying drawings, in which:

Figure 1 is a side elevation of a sleeping car incorporating the invention.

Figure 2 is a horizontal sectional view of the car taken on line 2—2 of Figure 3.

Figure 3 is a vertical sectional view of the car taken on line 3—3 of Figure 2.

Figure 4 is a sectional view of the car taken on line 4—4 of Figure 3.

Figure 5 is a transverse sectional view of the car taken on line 5—5 of Figure 3.

Figure 6 is a sectional view of the car taken on line 6—6 of Figure 3.

Referring now to the drawings by characters of reference, the sleeping car indicated generally

2 by numeral 10 is mounted upon a pair of wheel trucks 11 located one near each end thereof. The car flooring is arranged in three levels, the end floorings 12 being arranged to overlie the trucks. A lower flooring 13 extends horizontally between the trucks and in a plane slightly above the bearing plane of the truck wheels 14. This lower flooring is depressed from the end floorings and is connected therewith by upstanding floor portions 15. Extending in a horizontal plane above the lower flooring and overlying a major portion of the end floorings is an upper flooring 16. The car is provided with a conventional roof structure 17 and side walls 18 and with transverse walls or bulkheads 19 adjacent the extreme ends of the end floorings 12.

Bulkheads or transverse walls 19 are arranged at the ends of the lower flooring 13. A pair of spaced panels 20 extend centrally and longitudinally of the lower flooring between the bulkheads and are suitably attached to the lower and upper flooring 13 and 16 and provide therebetween a center aisle 21. The longitudinally extending spaces between the sides of the car and the aisle 21 panels of the lower flooring is divided into rooms, preferably of similar length, by transversely extending panels 22.

Centrally located spaced panels 23 extend longitudinally above the upper flooring 16 providing a center aisle 32 the full length thereof. These upper panels 23 are preferably in alignment vertically with the lower panels 20. The longitudinally extending spaces between the upper panels and the car side walls 18 and bulkheads 19 are divided by transversely extending panels 24 arranged preferably substantially the same distance apart. Such transverse panels are suitably secured to the roof, the upper flooring, the car outer side walls and the panels 23 to provide a series of compartments or rooms along each side of the upper aisle. Spaced panels 25, located centrally of the car, extend longitudinally between the end transverse panels of the upper deck to the bulkheads 19 adjacent the vestibule portions 26 of the car. These panels 25 are in line longitudinally of the car with panels 20 and 23 and form central aisles that align with the central aisle of the upper flooring. These panels 25 extend from the end floorings to the ceiling panel 27 that extends across the car below the roof forming end storage chambers 28. These chambers are accessible from the aisle through openings in the ceiling panel closed by doors 34. Chambers 30 extend across the car below the ends of the upper flooring and are closed at one

end by bulkheads 19. Such chambers are adapted to receive car equipment, such as water tanks, brake equipment and generators. The outer ends of these chambers 30 are enclosed by steps 31 that lead from the ends of the upper center aisle to the center aisle of the end floorings, such steps being removable to provide access to the chambers. The bulkheads 19 have openings closed by aisle doors 49' providing access to chambers 30. It will be seen that in order to pass from one end of the car to the other a passenger must travel over the center aisle of the end floorings, the steps 31 and the center aisle of the upper flooring.

The bulkheads 19 provide dead ends for the 15 lower deck and passenger access can be had to the lower deck only by means of a stairway between the upper and lower aisles, located preferably midway of the car. An upper room 34 and the room 35 therebelow are utilized to accommodate the stairway and the flooring 16 is formed with an opening for this purpose. The 20 stairway comprises a top flight of steps 39 leading down from the upper aisle toward the side of the car, a platform 40 at the base of such steps in a corner of room 35 and a lower flight of steps 41, next to the car side wall leading from the platform to flooring 13. The adjacent transverse panel is formed with an archway 45 open to a hallway 42 formed by partition wall 43 in the 25 room 44 adjacent room 35. The lower aisle panel adjacent the hallway is formed with an archway 44'. An archway 46 in the upper aisle panel is open to room 34 and steps 39. Transverse panel 47 extends along the inner side of steps 39 in room 35 to the roof in room 35 and longitudinal panel 48 extends along the inner side of steps 41 to the roof in room 34. Panel 48 extends longitudinally from panel 47 to the transverse panels 22 and 24 next to the hallway.

Room 44 has been shortened to form the hallway 42 and may be used for storage of equipment such as batteries. Chamber 50 in room 34 is formed by panels 47, 48 and 24 and the aisle panel and provides space for housing electric switches employed in the car equipment. Access to chamber 50 is had through an opening in the aisle panel that is closed by doors 51. A storage chamber is formed in room 35 below and beside the stairways and platform and an opening in the aisle panel for room 35 providing access to such chamber is closed by door 54.

Except for rooms 34, 35, and 44 and end rooms 39 and 54, the rooms are similar and accommodate passengers in privacy. They are equipped with a bed 55, seats 56 and 57, closets 53 and suitable toilet equipment (not shown). The aisle panels for the private rooms each have a door opening 58 and sliding doors 59 for the openings. The aisle panel for luggage storage room 39 has an archway 58' therein and the room is equipped with suitable shelves 70. The private room across from the luggage room is for the porter and both this room and the luggage room are slightly shorter than the other rooms.

Room 54 is divided into three sections by transverse panels 60 and 61, the upper part of end section 62 adjacent the porter's room providing a storage chamber for tables, linen etc., and the lower part forming a well 92 to receive the back 90 of chair 91 in the porter's room when moved to horizontal position to form a bed. The other end section 63 provides a toilet room. The intermediate section may contain a water cooler 65 and provides access to the toilet room door 66. Slid-

ing doors 95 are arranged to open or close openings in bulkheads 96 at the ends of the aisles adjacent the vestibules on the end portion of the end decks.

The rear transverse panel 24 for the porter's room has opening 67 therein closed by doors 68 through which the porter can have access from his room to the upper chamber in storage section 62. The aisle panel for room space 54 is formed with an archway 69 and panel 60 has an opening closed by door 71 for access to the chamber 28 above ceiling 27. Panel 24 at one end of the luggage room has an opening to the chamber 28 above ceiling 27 and is closed by door 72 accessible from the adjacent room.

It will be seen that the herein described car provides a maximum of private rooms within allowable railroad standard dimensions between the bulkheads on the lower and end floorings. The chambers adequately provide for storage of various accessories and light equipment, heavy equipment such as generators, tanks for the brakes, air conditioning equipment and water storage.

The invention may be modified in various respects as will occur to those skilled in the art and the exclusive use of all modifications as come within the scope of the appended claims is contemplated.

What is claimed is:

1. In a railway sleeping car carrying berths, a wheel truck near each end thereof, end floorings overlying the trucks, a lower flooring extending intermediate the trucks and in a horizontal plane above the lower flooring, an upper flooring extending longitudinally of the car above the end floorings and overlying a portion thereof and the lower flooring, said upper flooring providing a ceiling above the lower flooring, said floorings each having center aisles extending substantially the full length thereof and rooms along the full length of each side of said aisles, the rooms on the upper and lower floorings containing berths and of a length slightly greater than the length of the berths therein, the upper flooring having an opening therein in one room, a stairway leading from a lower room to the upper room floor opening, said stairway forming the sole means for occupants entering and leaving the lower flooring, and steps between the end of the upper aisle and the end flooring aisles.

2. In a railway sleeping car carrying berths, a wheel truck near each end thereof, end floorings overlying the trucks, a lower flooring dependent from the end floorings extending intermediate the trucks in a horizontal plane slightly above the bearing plane of the truck wheels, an upper flooring extending longitudinally of the car in a horizontal plane above the end floorings and overlapping a portion thereof, said upper flooring forming a ceiling above the lower flooring, a roof, side walls between the roof and the floorings, spaced aisle panels extending substantially throughout the length of the floorings, transverse walls dividing the entire length of the spaces between the aisle panels and the outer walls into rooms of similar length, the rooms on the upper and lower floorings containing berths and of a length slightly greater than the length of the berths therein, the upper flooring in one of the rooms having an opening therein, a stairway between the opening and the floor below and steps between the ends of the aisles of the upper flooring and the aisles of the end floorings.

3. In a railway sleeping car carrying berths, a

wheel truck near each end thereof, end floorings overlying the trucks, a lower flooring dependent from the end floorings and extending intermediate the trucks in a plane below the tops of the truck wheels, an upper flooring extending longitudinally above the lower flooring and portions of the end floorings, a roof, side walls between the roof and the floorings, spaced panels extending centrally substantially throughout the length of the floorings forming center aisles and side spaces, transverse walls dividing the entire length of the spaces between the aisle panels and the car side walls into rooms, the rooms on the upper and lower floorings containing berths and of a length slightly greater than the length of the berths therein, a stairway in one of the upper rooms leading away from the center aisle and continuing along the car side wall in spaced relation from the room aisle panel to the adjacent room therebelow, archways in the aisle panels of the rooms in which the stairway terminates, panels in the upper stairway room adjacent the stairway forming an upper storage chamber, the aisle panel of the upper stairway room having an opening leading to said chamber, and a door on the upper stairway room aisle panel for closing the opening.

4. In a railway sleeping car carrying berths, a wheel truck near each end thereof, end floorings overlying the truck, a lower flooring dependent from the end floorings extending intermediate the trucks in a plane below the tops of the truck wheels, an upper flooring extending longitudinally of the flooring of the car above the lower flooring and portions of the end floorings, a roof, side walls between the roof and the floorings, spaced panels extending lengthwise of the floorings and forming center aisles and side spaces substantially the full length thereof, transverse walls dividing the entire length of the side spaces between the aisle panels and the car side walls into rooms, the rooms on the upper and lower floorings containing berths and of a length slightly greater than the length of the berths therein, a stairway leading from the upper center aisle in one of the rooms toward the adjacent car side wall and continuing along the car side wall downwardly in the room thereunder, a hallway in the room adjacent the bottom of the stairway leading to the aisle, panels in the lower room housing the stairway and with the stairway forming a storage chamber, the aisle panel adjacent said storage chamber having an opening therein, and a door on the lower aisle panel for closing said opening.

5. In a railway sleeping car carrying berths, a wheel truck near each end thereof, a roof, side walls, end floorings over the trucks, a lower flooring dependent from the end floorings and having a horizontal portion extending between the trucks, an upper flooring extending longitudinally of the car in a horizontal plane above the lower flooring and a portion of the end floorings, panels between the lower and upper floorings forming a center aisle and side spaces, panels between the roof and the end and upper floorings forming a center aisle and side spaces extending substantially the full length of the car, bulkheads across the ends of the horizontal portion of the lower flooring and adjacent the outer ends of the end floorings, steps between the ends of the upper aisle and the end flooring aisles, transverse panels dividing substantially the entire length of the side spaces between the bulkheads into rooms, the rooms on the upper and lower floorings containing berths and of a length slightly greater than

the length of the berths therein, and a stairway connecting an upper and lower room midway of the car forming the only means for passengers to enter and leave the lower flooring.

6. In a railway sleeping car carrying berths, a wheel truck near each end, a roof, side walls, end floorings over the trucks, a lower flooring dependent from the end floorings and having a horizontal portion between the trucks in a plane adjacent the bearing portions of the truck wheels, an upper flooring extending longitudinally in spaced relation above the lower flooring and a portion of the end floorings, panels forming center and side spaces substantially the entire length of the floorings, transverse walls throughout the length of the side spaces between the side panels and the side walls forming rooms, bulkheads at the ends of the horizontal portion of the lower flooring having openings in line with the lower flooring aisle, doors closing the openings in the bulkheads and accessible from the lower aisle, some of the rooms between the bulkheads and the ends of the upper flooring forming storage chambers for car equipment and the other rooms carrying berths, the sleeping rooms on the end floorings and the rooms on the upper and lower floorings carrying berths and such rooms being of slightly greater length than the berths, and steps leading from the ends of the upper flooring aisle to the aisles of the end floorings and from the center of the upper flooring to the lower flooring.
7. In a railway sleeping car carrying berths a wheel truck near each end, a roof, side walls, end floorings over the trucks, a lower floor dependent from the end floorings and having a horizontal portion between the trucks in a plane adjacent the bearing portions of the truck wheels, an upper flooring extending longitudinally in spaced relation above the lower flooring and a portion of the end floorings, bulkheads across the ends of the horizontal portion of the lower flooring and adjacent the outer ends of the end floorings, the spaces between the lower bulkheads and the ends of the upper flooring forming equipment storage chambers, aisle forming spaced panels extending longitudinally of the car between the upper and lower bulkheads, transverse panels throughout the length of the spaces between the aisle panels, the car sides and the bulkheads defining rooms, such transverse panels closing the end of the storage chambers at each side of the ends of the upper flooring, the rooms on the upper and lower floorings containing berths and of a length slightly greater than the length of the berths therein, and removable steps between the ends of the upper flooring aisle and the end flooring aisles closing the space between the transverse panels at the ends of the chambers.
8. In a railway sleeping car carrying berths, a wheel truck near each end, a roof, side walls, end floorings over the trucks, a lower floor dependent from the end floorings and having a horizontal portion between the trucks in a plane adjacent the bearing portions of the truck wheels, an upper flooring extending longitudinally in spaced relation above the lower flooring and a portion of the end floorings, bulkheads across the ends of horizontal portion of the lower flooring having central openings therein, doors closing the openings in the bulkheads and accessible from the space between the bulkheads, the spaces between the bulkheads and the ends of the upper flooring forming storage chambers for car equipment, steps between the upper flooring and the lower flooring

intermediate the bulkheads, spaced panels extending longitudinally the entire length of the horizontal portion of the lower flooring and substantially the entire length of the upper and end floorings forming center aisles and side spaces, transverse walls throughout the length of the spaces between the car side walls and the aisle panels forming rooms, the rooms on the upper and lower floorings containing berths and of a length slightly greater than the length of the berths therein, and removable steps leading from the ends of the upper aisle to the end flooring aisles, the chambers being accessible through the opening between the ends of the upper flooring and the lower flooring when the steps are removed.

9. In a railway sleeping car carrying berths, a wheel truck near each end thereof, end floorings overlying the trucks, a depressed flooring between the trucks connected with the end floorings, a longitudinally extending upper flooring in a plane above and overlying portions of the end floorings, a roof, side walls, longitudinally extending panels between the end and upper floorings and the roof providing center aisles and side spaces substantially the full length of the floorings, transverse walls throughout the length of the side spaces defining rooms, the rooms on the upper and lower floorings containing berths and of a length slightly greater than the length of the berths therein, steps between the ends of the upper flooring aisle and the end flooring aisles, one end room on one side of an end flooring aisle being adapted to receive luggage and the end room across the aisle from the luggage room being adapted to accommodate a porter, the aisle panels for the baggage and porter rooms having openings therein beyond the adjacent steps, and a door for the opening in the panel of the porter's room.

10. In a sleeping car carrying berths, a wheel truck near each end, floorings over the trucks, a flooring extending longitudinally of the car in a plane above and overlying a portion of the end floorings, a roof, car side walls, spaced panels extending longitudinally substantially the entire length of the floorings forming aligned center aisles and side spaces, transverse walls dividing the spaces between the aisle panels and the car sides into room spaces, the rooms on the upper and lower floorings containing berths and of a length slightly greater than the length of the berths therein, an end room being for use by the porter, a transverse panel in the room space next to the porter's room forming a closet space, the transverse panel of the porter's room adjacent the closet space having an opening therein, and a door for closing the opening and accessible only from the porter's room.

11. In a sleeping car carrying berths, a wheel truck near each end, floorings above the trucks, a flooring extending longitudinally of the car in a plane above and overlying a portion of the end floorings, a roof, car side walls, spaced panels extending longitudinally of the floorings forming aligned center aisles and side spaces substantially the full length of the car, transverse walls dividing the side spaces into room spaces, the rooms on the upper and lower floorings containing berths and of a length slightly greater than

the length of the berths therein, an end room on the end flooring being for use by the porter, a transverse panel in the room space next to the porter's room forming a closet space, the transverse panel of the porter's room adjacent the closet space having an opening therein, a ceiling in the porter's room and over the closet space forming an upper storage chamber, the transverse panel forming the closet extending to the roof and having an opening therein for access to the upper chamber from the room space adjacent the porter's room, end doors for closing the openings in the transverse panels.

12. In a sleeping car, carrying berths, a wheel truck near each end, floorings over the trucks, a flooring extending longitudinally of the car in a plane above and overlying a portion of the end floorings, a roof, car side walls, spaced panels extending longitudinally substantially the full length of the floorings forming aligned center aisles and side spaces, transverse walls dividing the side spaces into room spaces, one of the end room spaces on the end flooring being equipped for luggage and the space adjacent thereto being equipped for a passenger, the rooms on the upper and lower floorings containing berths and of a length slightly greater than the length of the berths therein, a ceiling over the luggage room forming a storage chamber thereabove, said transverse panel intermediate said rooms having an opening for access to the chamber, and a door on said panel for closing the opening therein and accessible from the passenger room.

13. In a railway sleeping car carrying berths, side walls, a roof, end wheel trucks, end floorings over the trucks, upper flooring intermediate and overlying a portion of the end floorings, a bulkhead adjacent the outer end of each end flooring, spaced panels extending longitudinally of the floorings between the bulkheads forming center aisles and side spaces, and transverse walls throughout the length of the longitudinal side spaces of the upper and end floorings forming rooms along both sides of and substantially the entire length of the car, the rooms on the upper flooring and some of the rooms on the end floorings carrying berths and being slightly greater in length than the berths.
